United States Patent Office.

ROBERT NEWTON, OF JERSEYVILLE, ILLINOIS.

Letters Patent No. 93,636, dated August 10, 1869.

IMPROVEMENT IN ROLLING-CUTTER FOR PLOWS.

The Schedule referred to in these Letters Patent and making part of the same.

To all whom it may concern:

Be it known that I, ROBERT NEWTON, of Jerseyville, in the county of Jersey, and State of Illinois, have invented a new and useful Improvement in Rolling-Cutters for Plows; and I do hereby declare that the following is a full and exact description of the same, reference being had to the accompanying drawings, and to the letters of reference marked thereon.

This invention relates to an improved method of journaling revolving cutters, and consists mainly in forming a circular orifice through the centre of the cutter, and inserting a wooden socket or bushing; said bushing being held by wedge-shaped projections on the bore of the orifice, as will be more fully described hereinafter.

In the drawings—

Figure 1 is a side elevation of my invention, and

Figure 2, a transverse vertical central section of the same.

To enable others skilled in the art to make and use my invention, I will proceed to describe fully its construction and method of operation.

A represents the cutter, which is composed of a circular plate, with the periphery sharpened to form a cutting-edge.

B B represent flanges, rigidly attached to the centre of the cutter A, and

C is a circular orifice, extending through the centre of the flanges and cutter.

c c represent wedge-shaped projections, on the bore of the orifice C, which extend longitudinally of the same.

D represents a cylinder of wood, which has an orifice, C', and is made of suitable size to fit the orifice C, into which it is driven. The orifice C' is of suitable

size to receive the pin or bolt on which the cutter revolves.

The operation of my invention will be readily understood. The wooden socket or bushing D is driven into the orifice C, and the wedge-shaped projections c crowding the particles together, render its attachment secure. The axis or pin on which the cutter revolves is introduced through the orifice C', and the cutter is attached to the plow-beam.

The common manner of constructing revolving cutters is simply to bore out the socket for the axis in metal, but as dirt and rust are liable to accumulate at that point, the bore soon becomes so much worn as to render the cutter almost useless, and also difficult and expensive to repair. My plan, however, effectually obviates this difficulty, as the plowman can easily carry one or more bushings while at work, and when one becomes worn out, another can be readily inserted, thus effecting a great saving of time and expense.

In the old method, when the bore becomes worn, it is necessary to suspend work, and go to the nearest town, which is often at a distance, to procure another cutter, thus involving considerable expense.

Having thus fully described my invention,

What I claim as new, and desire to secure by Letters Patent, is—

In a revolving cutter, the wooden bushing D, substantially as described, and for the purpose set forth.

This specification signed and witnessed, this 7th day of June, 1869.

ROBERT NEWTON.
